UNITED STATES PATENT OFFICE.

JOSEPH H. APPLETON, OF OSHKOSH, WISCONSIN, ASSIGNOR TO LEACH COMPANY, OF OSHKOSH, WISCONSIN, A CORPORATION OF WISCONSIN.

BROOM FOR STREET-SWEEPING MACHINES.

Application filed June 15, 1925. Serial No. 37,016.

The invention relates to street-sweeping machines, and is particularly concerned with an improved broom for use in such machines.

5 The principal object of the invention is to provide a broom of the character described which will sweep a surface thoroughly without streaking the same.

Other objects and advantages of the invention will undoubtedly occur to those skilled in the art upon an understanding of the construction and arrangement of the broom.

In order that the invention may be readily understood, one structural embodiment of the same is presented in the accompanying drawings and following description, but such embodiment is intended merely for the purpose of exemplification as the invention 20 is obviously susceptible of embodiment in other structurally modified forms coming equally within the comprehensive scope of the appended claims.

In the drawings:

25 Fig. 1 is a side view of a portion of a street-sweeping machine equipped with the broom of the invention;

Fig. 2 is a sectional view taken on the line 2—2 of Fig. 1; and

30 Fig. 3 is a sectional view through one of the bristle retaining members of the broom, showing the component parts of the member in separated relation.

As will be observed in the drawings, the 35 broom of the invention is a medially articulated structure, composed of two generally similar broom sections 10 and 11 which are arranged angularly in end to end relation with the bristles at the inner end of one section lapped with those of the other to present an uninterrupted expanse of bristles throughout the length of the broom.

The street-sweeping machine with which the broom is associated includes a main 45 frame 12. A counter-shaft 13 extends transversely of the frame 12, and is journaled in two bearing brackets 14 which are mounted on the sides of the same. The broom is rotated from the counter-shaft 13, and the counter-shaft is in turn rotated from a suit-

able source of power on the machine through a chain and sprocket connection 15.

The broom sections 10 and 11 are supported in a vertically-movable frame which consists of two side bars 16 and a medially angulated axle 17. The bars 16 are pivotally secured to the brackets 14 concentrically of the axis of the counter-shaft 13, and extend at an inclination downwardly and rearwardly. The lower free ends of the bars 16 55 carry brackets 18 in which are fixedly secured the ends of the axle 17. The brackets 18 may be adjusted toward or away from the pivotal axis of the bars 16 by means of attaching bolts 19 and set screws 20. The 60 bolts 19 extend through aligned apertures in the bars 16 and brackets 18, and the apertures in the latter are elongated to permit of slight adjustment. The screws 20 provide adjustable abutments against which the 65 brackets 18 may bear. If a greater adjustment is desired than that possible with the slots in the brackets 18, the bolts 19 may be inserted through other apertures provided for that purpose in the bars 16. The axle 17 70 is positioned transversely of the frame 10 of the machine in a horizontal plane, with the ends of the axle in advance of the middle of the same, and the broom sections 10 and 11 75 are journaled upon the two straight portions 21 and 22 of the axle.

Each of the two broom sections 10 and 11 consists of two spaced journaling hubs 23 and 24 which are connected at corresponding spherical points with a plurality of bristle-retaining members 25. The bristle-retaining members are composed of outwardly facing channel strips 26 in which the radially extending bristles 27 are clamped by rods 28.

The outer hub 23 of the broom section 10 is provided with a sprocket 29, and a chain 30 connects the sprocket 29 with a sprocket 31 on the collar shaft 13, whereby the broom section 10 is driven from the counter shaft. 85 Inasmuch as the plane in which the sprocket 29 and the chain 30 operate is at a slightly acute angle to the counter shaft 13, the peripheral portion 32 of the sprocket 31 is 90 tiltably associated with the hub portion 33 100

of the same in a ball-and-socket joint so that the sprocket 31 may remain in the plane of the sprocket 29 and chain 30 during the rotation of the counter shaft 13.

5. The inner hub 24 of the broom section 10 and the corresponding hub of the broom section 11 are provided with bevel gears 34 which mesh with each other at 35, whereby the broom section 11 is driven from the broom section 10. Inwardly of the bevel gears 34, the hubs 24 are provided with annular faces 36 which bear against each other at 37 and serve to maintain the broom sections in properly spaced relation. The brackets 18 provide thrust bearings at 38 which serve to prevent separative movement of the broom sections.

The bristle-retaining members 25 of each of the broom sections 10 and 11 are alternately long and short, and the bevel gears 34 are so meshed that the long members of one broom section are opposite the short members of the other section. This arrangement prevents the bristles of the broom sections fromlapping with each other and leaving a streak along the center line of the machine, the bristles instead being caused to lap first on one side of the center line and then on the other, as clearly shown in Fig. 2.

30 I claim:

1. A broom for street-sweeping machines, comprising two axle portions arranged angularly in end to end relation, and a medially articulated broom journaled on the axle portions.

2. A broom for street-sweeping machines, comprising a one-piece medially angulated axle, a frame in which the ends of the axle are rigidly supported, and two rotary broom sections journaled on the axle at opposite sides of the angle therein.

40 3. A broom for street-sweeping machines, comprising two rotary broom sections arranged angularly in end to end relation; each of said sections consisting of two spaced hubs, and a plurality of alternately long and short bristle-retaining members extending between corresponding peripheral portions of the hubs with the long members 45 of one broom section opposite the short members of the other, whereby to prevent streaking along a line beneath the junction of the sections.

50 4. A broom for street-sweeping machines, comprising two rotary broom sections arranged angularly in end to end relation; each of said sections consisting of two spaced hubs, a plurality of alternately long and short bristle-retaining members extending 55 between corresponding peripheral portions of the hubs with the long members of one broom section opposite the short members of the other, whereby to prevent streaking along a line beneath the junction of the 60 sections, and a bevel gear on the inner hub

of one broom section for meshing with the corresponding gear on the other.

5. In a street-sweeping machine, a power-transmitting shaft extending transversely of the machine, a frame hinged to swing about the axis of the shaft at the rear of the same, a medially angulated axle carried horizontally by the frame at the rear of the same with the two straight end portions of the axle converging rearwardly in equally spaced relation to the shaft, a medially articulated broom having the two sections thereof journaled on the two end portions of the axle in end to end relation, a driving connection from the shaft to one broom section, and another driving connection from that broom section to the other.

In testimony whereof I have hereunto subscribed my name.

JOSEPH H. APPLETON.

CERTIFICATE OF CORRECTION.

Patent No. 1,727,627.

Granted September 10, 1929, to

JOSEPH H. APPLETON.

It is hereby certified that error appears in the printed specification of the above numbered patent requiring correction as follows: Page 1, line 85, for the word "spherical" read "peripheral"; and that the said Letters Patent should be read with this correction therein that the same may conform to the record of the case in the Patent Office.

Signed and sealed this 1st day of October, A. D. 1929.

(Seal)

M. J. Moore,
Acting Commissioner of Patents.
